UNITED STATES PATENT OFFICE.

OLOF OHLSSON, OF SÖDERTELJE, SWEDEN.

VALVE OF THE ANNULAR TYPE.

1,383,842.

Specification of Letters Patent. Patented July 5, 1921.

Application filed May 28, 1918. Serial No. 237,165.

To all whom it may concern:

Be it known that I, OLOF OHLSSON, a subject of the King of Sweden, and resident of Skogsgatan 5, Södertelje, in the Kingdom 5 of Sweden, have invented certain new and useful Improvements in Valves of the Annular Type, of which the following is a specification, reference being had therein to the accompanying drawings.

10 This invention relates to valves of the annular type, in which the valve disk has an elongated shape, rectangular or oval for instance, and is connected with a central hub by straight arms extending from the hub of 15 the disk to the parts of the same, which have the longest radii. Owing to this arrangement the valve disk as a whole is carried by arms, the yielding capacity of which is considerably increased by their great 20 length, which results in the valve operating in a particularly suitable manner.

Figures 1 and 2 in the accompanying drawing are a longitudinal section and a side view respectively of a valve arranged in 25 accordance with this invention.

In the valve shown in the drawing the valve disk 1 is rectangular with rounded corners. The short side parts of the valve body are connected with the central part 30 or hub 3 by arms 2, the said hub 3 being fixed to the casing 4 by means of a screw bolt 5 with nuts 6 and a washer 7 being located between the hub and the said casing. To the valve disk 1 a disk 8 of leather or 35 the like is fixed by means of rivets, the shape of which disk 8 corresponds to the shape of the valve disk. Packing may, however, be provided on the valve seat. The illustrated valve is adapted to serve as an air 40 supply valve in an internal combustion engine, so that air is sucked through openings 9 provided in the valve casing, passes through openings 10 and the space between the opened valve disk and the seat both at

the outer and inner edges of the said disk. 45 According to the drawings the valve disk 1 is guided by pins 11 fixed in the valve casing and passed through openings provided in the arms 2. The valve disk may, however, be guided in any other suitable manner. 50 The springy arms 2 permit the valve to be opened and shut, after the air has entered the engine, or aid in shutting the same.

Owing to the long, springy arms 2, by which the valve disk is carried at its short 55 side parts, the valve disk will yield easily and consequently opens easily. While the valve disk is being opened, also the long side parts of the valve disk move substantially parallelly to themselves, so that the valve 60 disk, in spite of its elongated shape, is opened substantially uniformly all around. The length of the stroke of the valve disk during the opening operation may be increased, so that the size of the valve disk 65 may be correspondingly reduced for the admitting of the same air quantity, without any hissing sound being produced in the valve during the entrance of the air.

The valve disk is preferably stamped from 70 sheet metal, which operation is easily effected owing to the straight shape of the arms 2.

Having now described my invention, what I claim as new and desire to secure by Letters Patent is:

A valve of the annular type comprising, 75 an elongated disk having a central hub, yielding arms extending radially straight the greatest distance from said hub to and connecting with said disk, and means fixing 80 the hub to the valve seat in order that the arms may force the valve disk against the said seat, said hub, disk and arms being formed integral and in the same plane.

In witness whereof, I have hereunto 85 signed my name.

OLOF OHLSSON.
